DESIGN FOR A DENTAL UNIT

Oscar H. Pieper and Alphonse F. Pieper,
Rochester, N. Y.

Application July 5, 1935, Serial No. 57,533

Term of patent 14 years

To all whom it may concern:

Be it known that we, Oscar H. Pieper and Alphonse F. Pieper, citizens of the United States, residing at Rochester, in the county of Monroe and State of New York, have invented a new, original, and ornamental Design for a Dental Unit, of which the following is a specification, reference being had to the accompanying drawing, forming a part thereof.

We claim:

The ornamental design for a dental unit, as shown.

In witness whereof, I hereunto subscribe my name this 1st day of July, 1935.

OSCAR H. PIEPER.

In witness whereof, I hereunto subscribe my name this 26th day of June, 1935.

ALPHONSE F. PIEPER.
